UNITED STATES PATENT OFFICE

135,258

DESIGN FOR A KNITTING BAG OR THE LIKE

Gerald Murphy, New York, N. Y., assignor to Mark Cross Company, New York, N. Y., a corporation of New York

Application February 11, 1942, Serial No. 105,762

Term of patent 14 years

To all whom it may concern:

Be it known that I, Gerald Murphy, a citizen of the United States, residing at New York, county and State of New York, have invented a new, original, and ornamental Design for a Knitting Bag or the like, of which the following is a specification, reference being had to the accompanying drawing, forming part thereof.

Fig. 1 in the drawing is a perspective view of a knitting bag or the like, showing my new design, and Fig. 2 is a similar view of the bag as it appears from the opposite side.

The characterizing features of the design reside in the bag of the proportions and configuration illustrated, comprising a bag of flexible material having a flat circular bottom with a full

rounded side wall rising therefrom and gathered in a neck portion terminating at the top in a widespread flaring open mouth and a long wide handle of flat relatively stiff material secured flat against said mouth portion tending to hold the same in open expanded shape, said handle extending upwardly from said point of attachment and thence looped downwardly and secured at the lower end flat over the lower portion of the side wall, stiffening and holding the latter in outwardly rounded condition above the circular bottom.

I claim:

The ornamental design for a knitting bag or the like, substantially as shown and described.

GERALD MURPHY.
